UNITED STATES PATENT OFFICE.

HENRY A. WAHLERT, OF ST. LOUIS, MISSOURI, ASSIGNOR TO THE ACME PIPE CLAMP COMPANY, OF ILLINOIS.

DESIGN FOR A PIPE-CLAMP.

SPECIFICATION forming part of Design No. 30,441, dated March 28, 1899.

Application filed September 14, 1897. Serial No. 651,688. Term of patent 14 years.

To all whom it may concern:

Be it known that I, HENRY A. WAHLERT, a citizen of the United States, residing at St. Louis, in the State of Missouri, have invented and produced a new and original Design for Pipe-Clamps, of which the following, taken in connection with the accompanying drawing, is a full and exact description.

The drawing illustrates in perspective a pipe-clamp having a form of configuration which embodies my design.

The design relates to clamps composed of two members A and B, each of which is of arc shape, as at *a b*, though the concave adjacent faces are each somewhat less than half a circle, so that the outline of the concave faces of the clamp is less than a true circle, and this constitutes the essential feature of my invention. One of said members, A, has

at its lower end a transverse slot, while the other, B, has a reverse curve *b'*, which passes through and rests in the transverse slot of the member A. The opposite end of members A and B extend radially from the conjoined curved or circular portions *a b* and have perforations in alinement, and the upper end of member A extends at right angles thereto.

Having thus particularly pointed out the shape or configuration of my new and original design, what I claim is—

The design for a pipe-clamp as herein shown and described.

In testimony whereof I hereunto attach my signature in the presence of two witnesses.

HENRY A. WAHLERT.
